W. H. SCHOONMAKER.
GAS ENGINE STARTING MECHANISM.
APPLICATION FILED FEB. 14, 1906. RENEWED SEPT. 13, 1912.

1,108,250.

Patented Aug. 25, 1914.

UNITED STATES PATENT OFFICE.

WILLIAM H. SCHOONMAKER, OF MONTCLAIR, NEW JERSEY.

GAS-ENGINE-STARTING MECHANISM.

1,108,250.

Specification of Letters Patent. Patented Aug. 25, 1914.

Application filed February 14, 1906, Serial No. 301,004. Renewed September 13, 1912. Serial No. 720,274.

To all whom it may concern:

Be it known that I, WILLIAM H. SCHOONMAKER, a citizen of the United States, and a resident of Montclair, in the county of Essex and State of New Jersey, have invented a new and Improved Gas-Engine-Starting Mechanism, of which the following is a full, clear, and exact description.

My present invention relates to a mechanism for starting internal combustion engines, particularly engines using a hydrocarbon fuel.

The invention also contemplates furnishing an auxiliary to the usual or normal operation of the engine by which on occasions of special load or stress to provide an extra supply of suitable vapor or other mixture, insuring thereby regular and powerful explosions.

Still a further object is to enable the starting mechanism to be used at will as an air compressor, furnishing compressed air for inflating the tires, blowing signals, and various other uses likely to occur in connection with automobile, marine or stationary engines.

The invention is intended to be applicable to a multiple cylinder gasoline engine plant, a pump being provided which connects with the carburetor and discharges into a receiver or tank, adapted to receive the gasoline vapor at a pressure sufficiently above atmospheric to give the vapor lively movement from the receiver when the controlling valve is opened. This reservoir has communication with the admission valve housing or housings of the engine. A valve controls this communication and this valve is connected with a gear for manually shifting the admission valve or valves in such a way that as the admission valve is opened the vapor valve is also opened, but as the vapor valve must be closed separately from the admission valves the said gear is arranged to move with the admission valves to closed position without affecting the vapor valve which is intended to be manually closed at a later period in the operation. Under this arrangement the tank may be furnished with an ample supply of gasoline vapor which may be admitted to the cylinders of the engine, the admission valve closed and by adjustment of the sparking mechanism the proper charge or charges fired and the engine started, after which the vapor valve may be closed manually or,

if desired, left open in which case the engine will be continually assisted by charges taken from the vapor reservoir in addition to those taken from the carburetor in the usual manner. I prefer to fit to the pump for supplying the vapor tank a peculiar connection enabling the carburetor and vapor tank to be cut out when desired, and the pump either run idly or employed for compressing air to be used for various purposes, as will be understood from the art.

I will now have reference to the accompanying drawing which illustrates as an example one manner in which my invention may be practically employed, in which drawings:

Figure 1 represents an elevation of a four cylinder engine with the admission valve housings in section on the line 1—1 of Fig. 75 2, the view also showing the pump, vapor tank and connections, and the means for manually operating the valves; and Fig. 2 is a section on the line 2—2 of Fig. 1.

10 indicates the engine cylinders and 11 the valve housings thereof.

12 indicates the admission valves which control communication between the chambers 14 and the interiors of the cylinders 10. Said chambers 14 communicate with a carburetor or other source of fuel mixture, and in fact may be considered as parts of the induction or fuel supply line. The exhaust valves are not illustrated: they may communicate with the housings 11, or may be otherwise seated in the cylinders as desired. The valves 12 may be mechanically or automatically operated. As here shown they are of the mechanically operated type, their stems 15 having springs 16 applied which hold the valves yieldingly seated. Said valves may be manually lifted from their seats by a gear consisting, according to the form of the invention illustrated, of elbow levers 16 articulated to a reach rod 17 to which a hand lever 18 is joined. This gear does not interfere with the usual operation of the admission valves, but enables said valves, by throwing the lever leftward from the position shown in the drawing, to be lifted from their seats at the will of the operator.

Connected with the engine to be driven therefrom, or driven in any other desired manner, is a pump 19, of which 20 is the induction pipe and 21 the eduction or discharge pipe. Said discharge pipe 21 leads to

a vapor reservoir 22, and in said pipe is arranged a three-way valve 23, the third port of which communicates with a nipple 23^a, which may be left in communication with the atmosphere or may be connected with the tires of an automobile or a separate reservoir, as desired. Interposed in the induction pipe 20 is a three-way valve 24, the third port of which communicates with a nipple 24^a, this nipple also being in communication with the atmosphere, as shown. The stems of the three-way valves 23—24 are joined by a link 25 which insures simultaneous operation of the valves so that when said valves are in the position shown in the drawing, gasoline vapor is taken from the carburetor through the pipe 20, and forced through the pipe 21 into the reservoir 22. When, however, the positions of the valves 23 and 24 are reversed, communication with the carburetor and with the vapor reservoir 22 is cut off, and the nipples 23^a and 24^a are connected with the pump so that it may be run idly or employed for compressing atmospheric air, as the operator desires.

Arranged in the vapor reservoir 22 is a perforate outlet pipe 26 which passes vertically to the upper part of the reservoir and communicates outside of the reservoir with a pipe line 27 having branches 28 passing respectively to the chambers 14 of the valve housings 11, so that the communication between said branch pipes 28 and the interior of the cylinders is controlled by the admission valves 12. The pipe 27 is provided with a check valve 29 preventing the return to the reservoir 22, and similar check valves 30 are arranged in the branch pipes 28. The pipe 27 also carries a valve 31 having attached to its stem an arm 32. With this arm coacts the curved finger 33 of a lever 34, which is in connection with the reach rod 17, so that as the lever 18 is thrown leftward from the position shown in the drawings, not only will the admission valve 12 be opened, but through its finger 33 the lever 34 will swing the arm 32 of the valve 31 and open the valve, this valve being closed during the action of the starting mechanism. As the lever 18 is returned to the position shown in the drawings to permit the springs 16 to close the valves 11, the finger 33 moves away from the arm 32 of the valve and leaves the valve open. Said valve may be subsequently closed at any time when it is desired to cut the starting mechanism out of operation. As shown best in Fig. 2 the branch pipes 28 enter the housings 14, and have nozzles 28^a arranged to deliver a jet diagonally through the valve seat, past the spark plug and into the cylinder, insuring the entry of the charge against atmospheric or other pressure that may be present in the cylinder, and tending also to cleanse the spark plug. This dispo-

sition of the nozzles 28^a serves also to create a suction in the chamber 14 and in the induction line connected therewith, thus assisting the normal operation of the carburetor.

In order to prevent the passage of the spark when the admission valves are open and avoid the danger of back firing in the pipe 27 and branches 28, I arranged contacts 35 in connection with the lever 18 in such a manner that as the lever is thrown leftward to lift the valves the primary or other circuit of the igniting system will be broken, thus preventing the development of the spark. As soon as the lever 18 is returned to the position shown, the contacts re-engage and the circuits close, permitting the operation of the sparking mechanism in the normal manner.

If desired the apparatus may be fitted with means for automatically cutting out the pump action as compression in the reservoir 22 reaches the desired point and to avoid such compression as might render ignition within the chamber possible. These means may be of any desired sort; as here shown they consist in a pressure cylinder 35^a fitted with a piston and regulating spring. The rod 36 of the piston has a fork 37 which is releasably engaged with the operating arm of the valve 23. By this arrangement as the pressure rises the valves 23 and 24 will be opened to the atmosphere, and as the pressure drops they will be automatically returned to vapor pumping adjustment. Should it be desired to adjust the valves manually the fork 37 may be disengaged from the valve 23, leaving the valves free.

In the operation of the invention, the pump 19 should be permitted to keep the reservoir 22 charged at all times with a gasoline vapor or other combustible mixture, so that upon stopping the engine the reservoir remains charged. In order to start the engine the lever 18 should be thrown leftward lifting the valves 12 from their seats and opening the valve 31. The compressed gasoline vapor will then flow through the branch pipes 28 and nozzles 28^a and said nozzles will cause the rich vapor from the tank 22 to be thrown in a jet past the spark plugs of the working cylinders and into the interiors thereof completely charging the cylinders of the engine, notwithstanding that some pressure may exist in the cylinders. When this has been done the lever 18 should be returned to its seat allowing the valves 12 to close and cut off the pipe branches 28 from communication with the interior of the cylinder. Then by properly adjusting the sparking mechanism or other igniting device and passing the spark within the cylinder or cylinders, the piston or pistons of which are in working stroke positions, explosions will be caused in said cylinders and the gases of combustion acting

on the said pistons will impart a movement to the engine. The operation of the engine then becomes normal, the charges being drawn from the carburetor in the usual manner through the chambers 14 and their connections (not shown), and these charges being supplemented by charges admitted through the pipes 28 from the vapor reservoir 22, the pump 19 acting continuously to recharge the reservoir. The engine may be allowed to operate in this manner as long as desired. Usually, however, upon the operation of the engine becoming normal the valve 31 should be closed, thus cutting out the auxiliary starting apparatus. If on an occasion of excessive load upon the engine, or other severe conditions, it is desired to accelerate the operation, the valve 31 may be manually opened admitting the extra charge from the branch pipes 28. The reservoir 22 should be fitted with a suitable gage, and the action of the pump 19 should be so regulated as to prevent development of excessive pressure in the reservoir. As the pressure becomes excessive the valves 23 and 24 may be operated either manually or automatically to cut the reservoir and carburetor out of communication with the pump.

Having thus described the preferred form 30 of my invention, what I actually claim and desire to secure by Letters Patent is:

1. An internal combustion engine having a means for establishing communication between the admission port and the source 35 of fuel mixture, a starting reservoir also communicating with the admission port, means for charging the starting reservoir with fuel mixture under pressure, a reservoir valve controlling communication between the reservoir and the admission port, and means for simultaneously opening said valve and the admission port of the engine.

2. An internal combustion engine having a means for establishing communication 45 between the admission port and the source of fuel mixture, a starting reservoir also communicating with the admission port, means for charging the starting reservoir with fuel mixture under pressure, a reservoir valve controlling communication between the reservoir and the admission port, and a manually operative means for simultaneously opening said valve and the admission port of the engine.

3. An internal combustion engine having a means for establishing communication between the admission port and the source 55 of fuel mixture, a starting reservoir also communicating with the admission port, means for charging the starting reservoir with fuel mixture under pressure, a reservoir valve controlling communication between the reservoir and the admission port, and means for simultaneously opening said valve and the admission port of the engine,

the last named means being arranged to leave the reservoir valve open upon the closure of the admission valve.

4. An internal combustion engine having a means for establishing communication between the admission port and the source of fuel mixture, a starting reservoir also communicating with the admission port, means for charging the starting reservoir with fuel mixture under pressure, a reservoir valve controlling communication between the reservoir and the admission port, and a manually operative means for simultaneously opening said valve and the admission port of the engine, the last named means being arranged to leave the reservoir valve open upon the closure of the admission valve. 70 75 80

5. An internal combustion engine having a means for establishing communication between the admission port and the source of fuel mixture, a starting reservoir also communicating with the admission port, means for charging the starting reservoir with fuel mixture under pressure, a reservoir valve controlling communication between the reservoir and the admission port, means for simultaneously opening said valve and the admission port of the engine, and means for rendering the engine ignition system inoperative during the operation of said means for simultaneously opening the valve. 85 90 95

6. An internal combustion engine having means establishing communication between the admission port and the source of fuel mixture, a pump having separate communication with the admission port and the source of fuel mixture, and means for cutting the pump out of communication with the admission port and source of fuel mixture, said means comprising three-way valves in the induction and eduction pipe lines, and a connection between the valves. 100 105

7. An internal combustion engine having a means establishing communication between the admission port and source of fuel mixture, an admission valve, a starting reservoir also communicating with the admission port, which communication is controlled by the admission valve, a pump for supplying fuel mixture to the starting reservoir, a valve controlling the outlet from the reservoir, manually operative means for lifting the admission valve, and a device in connection with said means for opening the outlet 110 115 120 valve of the reservoir.

8. An internal combustion engine having a means establishing communication between the admission port and source of fuel mixture, an admission valve, a starting reservoir 125 also communicating with the admission port, which communication is controlled by the admission valve, a pump for supplying fuel mixture to the starting reservoir, a valve controlling the outlet from the reservoir, 130 135

manually operative means for lifting the admission valve, and a device in connection with said means for opening the outlet valve of the reservoir, said means including a finger engaging a part in connection with the valve and adapted to leave said valve in the open position upon the return of the admission valve to its seat.

9. An internal combustion engine having means establishing communication between the admission port and a source of fuel mixture, a starting reservoir communicating with the admission port, a pump supplying fuel mixture to said reservoir, three-way valves respectively in the induction and ejection valves of the pump, and a connection between the valves to cause them to operate in unison.

10. An internal combustion engine having means for normally supplying fuel mixture, an auxiliary means for supplying fuel mixture independently of the first named means both of said means communicating with the admission port of the engine, an admission valve controlling both of said means, a device separate from the admission valve for controlling the said auxiliary means and a manually operative means for operating said device and the admission valve independently of the normal operation of the admission valve.

11. An internal combustion engine having means for normally supplying fuel mixture to the admission port of the engine, an auxiliary means for supplying fuel mixture to the engine, a valve controlling the auxiliary means and an operating device for the valve also having connection with the admission valve of the engine.

12. An internal combustion engine having a working cylinder with an admission port, an inlet valve controlling such port, a means for supplying fuel mixture to said port, an auxiliary fuel mixture supply also leading to such port and controlled by the valve thereof and means for manually unseating the valve.

13. An internal combustion engine having a working cylinder with an admission port, an inlet valve controlling such port, a means for supplying fuel mixture to said port, an auxiliary fuel mixture supply also leading to such port and controlled by the valve thereof, means for manually unseating the valve, and means controlling the auxiliary fuel supply connected to operate in unison with the means for unseating the valve.

14. An internal combustion engine comprising in combination a working cylinder having a charge-supply passage leading

thereto, a valve controlling communication between the charge-supply passage and cylinder, and an auxiliary fuel supply comprising an injector provided with means for supplying fuel thereto under pressure, said injector terminating in the charge-supply passage in close proximity to said valve and arranged to inject fuel-fluid under pressure past said valve and into the cylinder when said valve is raised from its seat.

15. An internal combustion engine comprising in combination a working cylinder having a charge-supply passage leading thereto, a valve controlling communication between the charge-supply passage and cylinder, a spark plug in said cylinder adjacent said valve, and an auxiliary fuel supply comprising an injector provided with means for supplying fuel thereto under pressure, said injector terminating in the charge-supply passage in close proximity to said valve and arranged to inject fuel-fluid under pressure past said valve and past said spark plug into the cylinder when said valve is raised from its seat.

16. An internal combustion engine plant comprising a plurality of working cylinders having charge-supply passages leading thereto, valves controlling communication between the charge-supply passages and cylinders, and an auxiliary fuel supply for said cylinders comprising means for supplying fuel under pressure, injectors connected therewith and terminating in said charge-supply passages in close proximity to said valves and arranged to inject fuel-fluid under pressure past said valves and into said cylinders when said valves are raised from their seats.

17. An internal combustion engine plant comprising a plurality of working cylinders having charge-supply passages leading thereto, valves controlling communication between the charge-supply passages and cylinders, and an auxiliary fuel supply for said cylinders comprising a supply pipe leading from a source of fuel-fluid under pressure, branch pipes leading from said supply pipe and terminating in said charge-supply passages in close proximity to said valves and arranged to inject fuel-fluid under pressure diagonally past said valves and into said cylinders when said valves are raised from their seats.

In testimony whereof I have signed my name to this specification in the presence of two subscribing witnesses.
